UNITED STATES PATENT OFFICE.

WILLIAM F. ANKLAM, OF DETROIT, MICHIGAN, ASSIGNEE TO C. M. HALL LAMP COMPANY, OF DETROIT, MICHIGAN, A CORPORATION OF MICHIGAN.

VEHICLE-LAMP.

1,123,205.

Specification of Letters Patent. Patented Dec. 29, 1914.

Application filed May 18, 1913. Serial No. 683,176.

To all whom it may concern:

Be it known that I, WILLIAM F. ANKLAM, a citizen of the United States of America, residing at Detroit, in the county of Wayne and State of Michigan, have invented certain new and useful Improvements in Vehicle-Lamps, of which the following is a specification, reference being had therein to the accompanying drawings.

10 The invention relates to lamps more particularly designed for use upon vehicles such as automobiles, and it is the particular object of the construction to provide means for altering the intensity of the light.

15 In the present state of the art various constructions have been devised for changing the intensity of the light in motor vehicle headlights, such as translucent or colored screens or adjustments for throwing the 20 lamp out of focus with the lens or reflector. There have also been constructed lamps having two lights of different intensity capable of being alternately used with the same reflector or lens, but all such constructions involve complexity and increase the cost of 25 manufacture.

With the present construction I have obtained the desired result by providing a main source of light having a reflector, and 30 an auxiliary source of light of considerably lesser intensity than the main source of light and provided with a reflector, the auxiliary source of light and its reflector being so positioned as not to interfere with the main 35 source of light, but the two sources of light and their reflectors being so associated as to illuminate the same path, that is—to throw the light in the same general direction.

The invention therefore consists broadly 40 in the combination of lights of different intensity having their respective reflectors so associated.

The invention further consists in the various features of construction and the combinations and arrangements of parts as hereinafter set forth.

In the drawings: Figure 1 is a vertical, longitudinal section through the lamp. Fig. 2 is a front elevation thereof.

50 (A) is the lamp of maximum intensity, which may be of any suitable construction but as shown consists of a parabolic case (B) inclosing a parabolic reflector (C).

(D) is a door for the front of a lamp 55 having a transparent face (E) in front of

the reflector and (F) is the source of light or illuminant arranged at the focal point of the reflector. This lamp is preferably an incandescent electric bulb which engages a suitable socket (G) arranged in rear of the 60 reflector and in registration with an aperture therein.

(H) are electric contacts for the socket (G), which are coupled to conductors (I) preferably passing through the space between the outer case and the reflector and connected to an external plug socket (J). This same socket (J) is preferably employed for connection with the lamp of lesser intensity as will be hereinafter described. 70

(K) is the smaller lamp which is preferably the same in its construction and organization as the main lamp (A), being provided with a parabolic reflector (L) and a door (M) having a translucent panel (N). 75

(O) is the electric bulb for the lamp (K), which is provided with a socket (P) preferably the same in size as the socket (G) so that the same fittings may be employed for each. The electrical connections to the lamp 80 (O) are formed by conductors (Q), preferably passing through the space between the case and reflector of the lamp (K) and thence downward through an aperture (R) and forward through a like aperture (S) into the 85 space between the reflector and case of the main lamp. From this point the conductor is passed to the socket (J) which is provided with two sets of terminal contacts (T) and (T'). 90

(U) is a plug member for the external connector which is provided with contacts (V) and (V') for cooperation with the contacts (T) and (T') respectively.

The lamp (K) may be mounted in any 95 desired relation to the main lamp (A) but I preferably arrange the same at the top of said main lamp supporting it by means of a bracket (W) which is attached to the case (B). The plane of the front of the smaller 100 lamp may be slightly in rear of the plane of the front of the main lamp, and the elevation is preferably such as to provide an unobstructed path for all of the rays from the parabolic reflector (L). 105

In use the connector (X) leads to a suitable source of current and controlling switch (not shown) which latter is so arranged that the current may be passed alternately through the bulbs (F) or (O). 110

2

Thus where the intense light is required the bulb (F) is used, and whenever it is desired to dim the light this is cut out and the current is sent through the bulb (O) of the 5 lesser light.

What I claim as my invention is:

1. In a headlight, the combination of a main source of light and an auxiliary source of light of lesser intensity than said main 10 source of light, said sources of light being adapted for alternate use, a main and an auxiliary reflector respectively for the main and the auxiliary sources of light, the auxiliary reflector being of considerably lesser size than 15 the main reflector, casings carrying both of said reflectors, electrical connections for both of said sources of light completely incased within said casings, and a common connector socket for said connections in one of said 20 casings.
2. In a headlight, the combination with a main electric bulb, an auxiliary electric bulb

of lesser intensity than and adapted for alternate use with the main bulb, a main and an auxiliary reflector respectively for the 25 main and auxiliary bulbs and arranged to throw the light from their respective bulbs in the same general direction, the reflector for the auxiliary bulb being of considerably lesser size than the main reflector, casings carrying both of said reflectors, said casings being arranged one above the other, a bracket upon the lower casing supporting the upper casing in position, electrical connections for the bulb completely inclosed by 30 said casings and bracket and leading to the bulbs, and a common connector socket for said connections.

In testimony whereof I affix my signature in presence of two witnesses.

WILLIAM F. ANKLAM.
